(57) **CLAIM**

The ornamental design for a laser comb, as shown and described.

DESCRIPTION

FIG. 1 is perspective view of a first embodiment of a design for a laser comb;

FIG. 2 is a bottom view of the first embodiment of a design for a laser comb;

FIG. 3 is a top view of the first embodiment of a design for a laser comb and of a second embodiment of a design for a laser comb;

FIG. 4 is a right side view of the first embodiment of a design for a laser comb;

FIG. 5 is a left side view of the first embodiment of a design for a laser comb;

FIG. 6 is a front view of the first embodiment of a design for a laser comb and of the second embodiment of a design for a laser comb;

FIG. 7 is a rear perspective view of the first embodiment of a design for a laser comb and of the second embodiment of a design for a laser comb;

FIG. 8 is a perspective view of the second embodiment of a design for a laser comb;

FIG. 9 is a bottom view of the second embodiment of a design for a laser comb;

FIG. 10 is a right side view of the second embodiment of a design for a laser comb; and,

FIG. 11 is a left side view of the second embodiment of a design for a laser comb.

The broken lines in the drawing are for illustrative purposes only and form no part of the claimed design.
